UNITED STATES PATENT OFFICE

JOHN SOKOL, OF MUSKEGON, MICHIGAN, ASSIGNOR OF FORTY-FIVE PER CENT TO WALTER MYKLAJEWSKI, OF MUSKEGON, MICHIGAN

DESIGN FOR A BUREAU

Application filed February 18, 1929. Serial No. 30,119. Term of patent 14 years.

To all whom it may concern:

Be it known that I, JOHN SOKOL, a citizen of Poland, residing at Muskegon, in the county of Muskegon and State of Michigan, have invented a new, original, and ornamental Design for Bureau, of which the following is a specification, reference being had to the accompanying drawing, forming part thereof, and in which—

I claim:

The ornamental design for a bureau as shown.

JOHN SOKOL.
